UNITED STATES PATENT OFFICE.

JACOB HENRY STULL, OF FREMONT, OHIO.

PERMUTATION LOCK.

Application filed March 6, 1924. Serial No. 697,398.

To all whom it may concern:

Be it known that I, JACOB H. STULL, a citizen of the United States, residing at Fremont, in the county of Sandusky and State of Ohio, have invented certain new and useful Improvements in Permutation Locks; and I do declare the following to be a full, clear, and exact description of the invention, such as will enable others skilled in the art to which it appertains to make and use the same.

My invention relates to permutation locks and has for its principal object to provide a device of this character which is of extreme simplicity and is therefore rather inexpensive, yet is highly efficient and desirable.

In the preferred form of the device, a substantially C-shaped shackle is provided, with its ends turned inwardly and disposed in alined spaced relation, and a rotatable barrel which controls the permutation locking means, normally receives both ends of the shackle, but is adapted to slide entirely onto one end thereof, when the lock is released. A further object is to provide novel co-acting means between the other end of the shackle and one end of the barrel, permitting release of the lock when it is impossible to see the same, for instance, at night.

With the foregoing in view, the invention resides in the novel subject matter herein-after described and claimed, the description being supplemented by the accompanying drawing.

Figures 1 and 2 are side elevations showing the device respectively locked and unlocked.

Figure 3 is an enlarged sectional view partly in elevation showing the device unlocked.

Figure 4 is an enlarged longitudinal sectional view showing the device locked.

Figure 5 is a disassembled perspective view of parts of the lock.

Figures 6 and 7 are transverse sections as indicated by lines 6-6 and 7-7 of Fig. 4.

In the drawings above briefly described, the numeral 1 designates a one-piece, substantially C-shaped shackle having its ends 2 and 3 turned inwardly and disposed in alined spaced relation, the end 2 being straight for a considerable distance and in the present showing, being provided with one longitudinal groove 4 and with three transverse or circumferential grooves 5, 6

and 7, all of which communicate with the groove 4. A sleeve 8 frictionally surrounds the shackle end 2 and is both rotatable and slidably thereon, said sleeve being by preference split longitudinally as indicated at 9, to allow it to frictionally grip the shackle end in an effective manner. I have shown this sleeve provided with an inwardly extending stud 10 which is received normally in the groove 6, but is also adapted to be received in the longitudinal groove 4, as will be hereinafter more fully explained. The sleeve 8 is also provided with a transverse slot 11 from its exterior to its interior, which slot registers with the groove 5.

Rotatably surrounding the sleeve 8, I have shown an operating barrel 12, one end of which receives the shackle end 3 when the device is locked as shown in Figs. 1 and 4, or is about to be locked. This barrel is provided with a stud 13 which extends inwardly, entirely through the slot 11, and has its inner end received in the groove 5. It will thus be seen that by proper manipulation of the barrel 12, the stud 13 will engage an end of the slot 11 and move the sleeve 8 until its stud 10 is alined with the groove 4. Then, further turning of the barrel 12 to the proper extent, will aline the inner end of the stud 13 with said groove 4. Thus, the barrel 12 and sleeve 8 may be bodily moved back upon the shackle end 2 to expose the other end 3 of the shackle.

Preferably, although not necessarily used in connection with the features above described, is a second sleeve 14 which slidably and rotatably surrounds the shackle end 2 and is confined between the inner end of the sleeve 8 and an internal shoulder 15 with which the barrel 12 is provided, said sleeve 14, like the sleeve 8 being housed within said barrel. The sleeve 14 is provided with a stud 16 received in the groove 7 when the device is locked, but the inner ends of the sleeves 8 and 14 are shaped to provide spaced co-acting shoulders 17, by means of which said sleeve 14 may be turned, when the sleeve 8 is turned. Thus, by proper manipulation of sleeve 8, under the influence of the barrel 12, the sleeve 14 may be positioned to dispose its stud 16 for movement in the longitudinal groove 4.

I have stated above, that it is not essential to use the sleeve 14, and it is to be understood that when this sleeve is not employed, the additional groove 7 of the

- shackle end 2, is not necessary. I prefer however to use the two sleeves and the general association shown, but at this point, it may be further explained that the exact 5 relation of longitudinal and transverse grooves, and inwardly projecting pins herein disclosed, is not essential, as other suitable arrangements could be used. In this connection, attention may be directed 10 to a notch or groove 18, formed in the inner extremity of the shackle end 2 and communicating with the groove 7. This notch or groove is instrumental when initially applying the sleeves 8 and 14, as their inwardly 15 extending studs 10 and 15 may be passed through said notch or groove into the groove 7 and turned within the latter, until they can be slid inwardly within the longitudinal groove 4.
- 20 Upon the shackle end 3, I have shown a projection 19 which co-acts with a number of notches, grooves or the like 20 in the adjacent end of the barrel 12, each of said notches or the like having an identifying 25 number. Thus, by setting the barrel 12 with one of the notches engaged with the pin 19, a starting point is provided. The barrel is then turned a specified amount in one direction, next is turned to a predetermined 30 extent in the other direction, and is finally turned in the first named direction to a certain degreee. This manipulation of the barrel 12 will aline the three studs 10, 13 and 16, with the longitudinal groove 4 and the 35 barrel and contained sleeves may then be slid backwardly upon the shackle end 2, to release the lock. Obviously, a reversal is necessary to lock the device.
- 40 Preferably one of the grooves or the like 20 is deeper than the others, or provision is otherwise made for identifying this particular groove, even though it cannot be seen. By this provision, the starting point 45 for opening the lock may readily be determined at night and by counting the proper number of "clicks" as the notches 20 successively engage the projection 19, it will be seen that the barrel 12 may be manipulated in the proper manner for opening the lock.
- 50 As excellent results have been obtained from the details disclosed, they are preferably followed, but within the scope of the invention as claimed, numerous minor changes may be made.

I claim:—

1. A lock comprising a shackle having a straight portion formed with registering longitudinal and transverse grooves, a sleeve frictionally surrounding said straight portion of said shackle and having a stud received normally in a transverse groove thereof but adapted for reception also in a longitudinal groove of said shackle portion, said sleeve having a transverse slot from its exterior to its interior, and an operating barrel rotatably surrounding said sleeve and having a stud extending inwardly through the aforesaid slot and normally received in a transverse groove of said straight shackle portion, the last named stud being adapted 60 also for reception in a longitudinal groove of said shackle portion when the first named stud is similarly positioned, whereby the barrel and sleeve as a unit are longitudinally 65 slidable with respect to the shackle. 70

2. A structure as specified in claim 1; together with an additional sleeve frictionally surrounding said straight shackle portion within said barrel and having a stud normally received in a transverse groove thereof 80 but adapted also for reception in a longitudinal groove of said shackle portion, the two sleeves being in abutting relation and having spaced co-acting shoulders for turning one by means of the other, said barrel 85 having a shoulder abutting the outer end of the additional sleeve to prevent movement of the latter away from the first named sleeve.

3. A lock comprising a shackle of substantially C-shape with its ends turned inwardly into spaced alined relation, a barrel slidable and rotatable on said shackle ends and adapted to be moved entirely onto one of said ends, a projection on the other end of 95 said shackle normally abutting an end of the barrel, and permutation locking means for said barrel disposed within and operable by the same, said end of said barrel having notches to successively engage said 100 projection when the barrel is turned to operate said permutation locking means, provision being made for identifying one of said notches without viewing the same.

In testimony whereof I have hereunto af- 105 fixed my signature.

JACOB HENRY STULL.
